UNITED STATES PATENT OFFICE.

FRANK J. DIACONT, OF PROVIDENCE, RHODE ISLAND; ASSIGNOR TO THE
H. H. CURTIS COMPANY, OF NORTH ATTLEBOROUGH, MASSACHUSETTS:

DESIGN FOR A BRUSH-BACK OR SIMILAR ARTICLE.

SPECIFICATION forming part of Design No. 31,705, dated October 24, 1899.

Application filed September 27, 1899. Serial No. 731,868. Term of patent 3½ years.

To all whom it may concern:

Be it known that I, FRANK J. DIACONT, a citizen of the United States, residing at Providence, in the county of Providence and State 5 of Rhode Island, have invented and produced a certain new and original Design for the Back of a Brush or Similar Article, of which the following is a specification, reference being had therein to the accompanying drawings.

Figure I is a plan view of a brush-back, showing my new design. Fig. II is a central vertical section of the same.

The ornamentation of the handle B begins 15 with a shield a, supported by inwardly-disposed scrolls b b, which embrace a conventionalized beaded stalk c, that expands downwardly in the form of foliates and foliated scrolls. Embracing the shield a on either side 20 rise stalks g g, entwined with tendrils and extending upwardly to the base of the body ornamentation. These stalks, in conjunction with the rows of spherical beading i i below, afford a beaded contour for the entire handle 25 ornamentation. The crest of the shield bears a flower j, from which project upwardly a mass of leaves and buds.

The brush-body A contains a central escutcheon o, encompassed on all sides by a 30 mass of floral, scroll, shell, and bead ornamentation, disposed substantially as follows: Below the escutcheon is an oblong plain ornament d, from which spring on either side upwardly and inwardly directed scroll series

e e, interlaced with smaller foliated scrolls. 35 Beneath d are converging shell ornaments h, embracing a flower k, which is surrounded by leaves and buds. Above the escutcheon rests a flower l, forming the base of right and left scrolls surmounted by a tripart crest m, 40 whence spring downwardly-directed scrolls n n with several intermediate branches p p.

Throughout the upper body ornamentation above outlined are interspersed minute scroll and foliate ornaments. The body has its outer 45 margin defined by varied circular-bead series, the upper ones s s extending on either side to points nearly opposite the escutcheon-top, while the lower series u u extend upwardly 50 along the margin of the lower body ornamentation.

A noticeable feature of my design is the bold and pronounced relief of all the parts thereof.

It is apparent that this design is also applicable to mirror-backs and other similar articles. 55

Having described my invention, what I claim as new, and desire to secure by Letters Patent, is— 60

The design for a brush-back or similar article, as herein shown and described.

In testimony whereof I affix my signature in presence of two witnesses.

FRANK J. DIACONT.
